H. EPSTEIN

FOLDING UMBRELLA

Filed Jan. 29, 1927

Patented Apr. 17, 1928.

1,666,692

UNITED STATES PATENT OFFICE.

HARRIS EPSTEIN, OF ROCKAWAY BEACH, NEW YORK.

FOLDING UMBRELLA.

Application filed January 29, 1927. Serial No. 164,469.

This invention relates to umbrellas of the folding type which are adapted to be collapsed and adjusted into small compass so that they may be readily carried in a small hand bag, in the pocket and otherwise, and which may be readily opened out into using position whenever the occasion requires.

A specific object of the invention is to provide a folding umbrella in which the ribs may be readily folded together with the cover wrapped around them and the stick may be folded down towards the folded together ribs, so that the entire umbrella will occupy a comparatively small compass.

These being among the objects of the present invention, the same consists of certain features of construction and combinations of parts to be hereinafter described and then claimed, with reference to the accompanying drawings which show one embodiment of the invention, and in which:

Fig. 1 is a partially sectional view of an open umbrella embodying the invention, the section being on line 1—1 (Fig. 2);

Fig. 2 is a plan;

Fig. 3 is an enlarged section of parts adjacent the cover of the umbrella;

Fig. 4 is an enlarged transverse section on line 4—4 (Fig. 1), and

Fig. 5 is an elevation of the completely folded umbrella, the cover being broken away for the sake of clearness.

The drawings illustrate a very simple, yet possible form of umbrella, that is to say the umbrella there shown is provided with four ribs for supporting a rectangular cover, but it is clear that the number of ribs may be increased and the shape of the cover accordingly altered.

The stick 10 of the umbrella is preferably constructed, as follows: A central supporting pin or stem 11 is provided to which the cover 12 of suitable rain proof material is attached. The pin 11 is connected by a pivot 13 with a short rod 14 which is tightly secured in one end of a metallic tube 15. In the other end of the tube 15 there is tightly secured one end of a longer rod 16, the two rods 14, 16 and the tube 15 being in axial

alignment so as to constitute the extended portion of the stick 10, which is terminated by the supporting pin or stem 11. The parts concomitant to the stick 10 will be described later on. The terminal pin or

stem 11 of the stick 10 is preferably cylindrical so as to provide a stud upon which

the ribs of the umbrella may swivel. One of the ribs 17, as shown clearly in Fig. 4, is directly fixed to the pin or stud 11 which, as shown in Fig. 4, is in the form of a tube, 60 which tubular pin 11 is provided with a head or enlargement 18 which is preferably that part of the pin into which the inner end of the rib 17 is securely and rigidly fixed. It will be noted that the ribs 17 and 65 the pivot 13 are arranged substantially at right angles with respect to each other so that the extended portion of the stick, which is beyond the pivot, may be folded towards the said rib 17. The other ribs 19 of the 70 umbrella are similar, and hence the same numeral will indicate each one of them, and there may be as many of these ribs as desired, although only three of them are shown. The three ribs 19 are respectively 75 provided with collars 20, 21 and 22, and these collars are successively strung on the terminal pin or stem 11 one after the other so as to rest upon the head or enlargement 18. A washer 24 is provided under the 80 cover 12 which is placed on the pin or stem 11 and it and the cover 12 are held upon the stick by means of a rivet like or other fastening 25, in such manner that the three collars 20, 21, 22 will be confined between 85 the head 18 and said washer 24.

It will be seen that the collars 20, 21, 22 of the ribs 19 fit snugly yet loosely upon the pin 11 so that each of said ribs has a swivel connection with the said terminal pin 11 of 90 the stick. Each of the ribs 17 and 19 may, if desired, be of a length to extend to the edges of the cover 12, but preferably the said ribs are shorter than the distance between the stick 10 and the edges of the cover, to 95 permit of the use of tubular rib extensions 19^a, and these tubular extensions 20 telescope onto the ribs proper 17 and 19, so that the ribs may be lengthened or shortened, as desired. The outer edges of the cover 12 are 100 secured by connections 21 to the outer extremities of the rib extensions 19^a. It will be seen that when the umbrella is opened by swiveling the ribs around the pin or stud 11, and the telescopic connections 19^a pulled outwardly, the cover 12 of the umbrella will be spread and stretched. When it is desired to fold the ribs together, the telescopic connections are pushed inwardly toward the 105 stick and the ribs then folded towards each 110 other.

That portion of the stick which is ex-

tended beyond the pin or stick 11 and is pivoted thereto is provided with means for making the stick stiff as a whole or permitting the extended portion to be folded towards the ribs 17. Preferably such means comprises a longitudinally movable sleeve 26, guided upon the tubular section 15 of the stick and a spring catch 27, which may be retracted into a recess 28. It will be seen that when the catch 27 is allowed to engage with the adjacent end of the sliding sleeve 26, the sleeve will be engaged around the pivot 13 and the adjacent portions of the stick so as to hold the stick stiff throughout its length. However, when the catch 27 is depressed, the sleeve 26 may be slid towards the lower end of the stick for a distance sufficient to uncover the pivot 13 and the adjacent portions of the stick, thereby allowing the extended portion of the stick beyond the pin 13 to be folded down towards the ribs 17 and to be moved to substantially right angles with respect to the pin 11.

The outwardly extended position of the rib extensions 20 is limited by means of flexible connections 29, one end of each of which is secured to the inner end of a corresponding tubular extension 19^a, while the other end is secured to a flange 30 on the tubular member 15 of the stick.

The stick 10 is provided with a suitable handle 31 which has a tubular shank 32 that is adapted to telescope with the rod 16 of the stick. The telescoping of the rod 16 into the tube 32 is preferably for substantially the entire length of the handle 31. Suitable means are provided for holding the handle upon the stick so as to avoid its accidental loss and detachment and such means may comprise a flexible connection 33 which is attached to the handle 31 at one end and at its other end to the flange 30. A snap-catch 34 is provided upon the stick and it is in a position to snap over the inner end of the tubular shank 32 of the handle, thereby to hold the handle in its extended position.

The folded umbrella is illustrated in Fig. 5. Preferably to fold up the umbrella, the rib extensions 19^a are pushed inwardly upon the ribs 17, 19, so as to extend the lengths of the ribs; then the spring catch 27 is disengaged from the sliding sleeve 26 and the same moved from over the pivot 13 so as to expose it; then the swiveled ribs 19 moved towards the ribs 17 so that all of the ribs will stand in one direction; and then the catch 34 is released from the handle 31 so that it and its shank may be shoved inwardly on the extended portion of the stick 10 and the latter and handle 31 may be swung upon the pivot 13 and towards the folded together ribs. The cover may now be neatly folded about the parts of the frame so as to make a small package which may be placed in one's hand bag or the like.

The collapsed and folded umbrella takes up a very small space and can be readily unfolded and set for use.

It is obvious that the invention as described and illustrated is susceptible of modification without departing from the spirit of the invention as expressed in the scope of the appended claims.

What I claim as new is:

1. In a folding umbrella, the combination of a stick and ribs swiveled on the stick for folding together or for extending radially to spread the cover, the stick comprising a pivoted portion provided with a handle, the ribs when folded occupying a given position with respect to the upper part of the stick, and the pivoted portion of the stick mounted to swing toward such position of the folded ribs.

2. In a folding umbrella, the combination of a stick and ribs swiveled on the stick for folding together or for extending radially to spread the cover, the ribs being telescopic to stretch the cover and one of the ribs being rigid with the stick, whereby to maintain the stretched cover and the ribs against turning as a whole around the stick.

3. In a folding umbrella, the combination of a stick, collars loosely strung, one after the other, on one end of the stick, a collar rigid with the stick, and ribs extending from all of the collars, whereby the ribs may be folded together or extended radially, the folded position of the ribs being definitely determined by the rib on the rigid collar.

4. In a folding umbrella, a stick, a rib fixed radially to the stick, additional ribs swiveled on the stick to fold together toward the fixed rib to fold the cover or to be movable therefrom for supporting the cover in spread condition.

5. In a folding umbrella, a stick, a rib fixed radially to the stick, additional ribs swiveled on the stick to fold together toward the fixed rib or to be movable therefrom for supporting the cover in spread condition, and means for distending the cover after the cover has been spread, the fixed rib serving to prevent the turning of the distended cover around the stick.

6. In a folding umbrella, a stick, a rib fixed radially to the stick, additional ribs swiveled on the stick to fold together toward the fixed rib or to be movable therefrom for supporting the cover in spread condition, the stick comprising a supporting pin for the ribs, and an extended portion pivoted to the supporting pin, the pivot extending transversely with respect to the fixed rib.

7. In a folding umbrella, the combination of a supporting pin and an extended portion pivoted thereto, both constituting a stick, a rib fixed to and extending radially from and supported by the pin, additional ribs swiv-

eled on the pin to be foldable toward the fixed rib or to extend in opposite directions from the pin, all the ribs being telescopic, a cover for the umbrella and which is fixed to the free ends of the ribs, the fixed rib being at substantially right angles to the pivot, a sleeve slidable on the extended portion and

engageable over the pin, a catch to hold the sleeve in such engagement, a handle telescoping with the extended portion, means to hold the handle in outward position, and means to prevent the detachment of the handle. ¹⁰

HARRIS EPSTEIN.
